MULTIPLE GAS FEED SYSTEM FOR INTERNAL-COMBUSTION ENGINES OR THE LIKE

Roy K. Ensign, San Marino, Calif., assignor to
 Ensign Carburetor Company, Huntington Park,
 Calif., a corporation of California

Application December 6, 1949, Serial No. 131,397

3 Claims. (Cl. 48—191)

1

This invention has to do with feeding gaseous fuel from multiple sources to such a gas using unit as an internal combustion engine. The invention, although not limited to that, can best be initially described in connection with a use to which it is being currently put:

Sewer and sludge gases, generated in sewage disposal and treating systems, have combustible components which create fire and explosion hazards. As the gases have a utilizable heat content (averaging about 600 B. t. u. per cubic foot) it is desirable to burn them for some useful purpose and in many instances it is useful to use them for power generation. The amount of gas available from any given source per unit time commonly varies greatly, and a power plant capable of utilizing a peak or near-peak supply of the gases must be fed with a supplemental fuel when the supply drops, in order to maintain a sufficiently uniform power production to be economically useful.

The general purpose of the invention is to provide a fuel feed system which will automatically supply a supplemental fuel when, and to the extent that, it is necessary. The nature of the invention will be understood from the following description in connection with the accompanying drawing in which the single figure is a schematic representation of one illustrative form and application of the invention embodied in a dual gas feed system as applied to feeding the carburetor of an internal combustion engine.

In the drawings the element 10 may represent an internal combustion engine having its intake 11 connected to a carburetor 12. Operation of the engine draws air through the carburetor venturi 13, creating a sub-atmospheric pressure (depression) at gas port 14 at the Venturi throat. An adjustable valve 15 controls communication between port 14 and the gas intake 16 of the carburetor. Such an engine and carburetor system, at any given adjustment of valve 15 and any given level of engine operation, draws gas in at a pressure which is considerably below atmospheric. That is, the depression at gas port 14 is considerable.

In the drawing a feed pipe 20 feeds gas intake 16 from pressure regulator R which is fed via pipe 21, from any suitable source of the low-heat gas or vapor, such as is illustrated here by the tank 22. (The unit V in pipe 21 will be described later.) Any ordinary regulator will suffice, such as the simple regulator shown schematically with its pressure responsive diaphragm 25, high pressure intake 26, low pressure outlet 27, and its

inlet controlling valve 28 operated by its diaphragm and loaded by spring 29. In this particular instance where the delivery pressure of the regulator is set to be below atmosphere, the loading spring tends to close the valve, and inward movement of the diaphragm, exposed on its outer face to atmospheric pressure, opens the valve when the pressure in diaphragm chamber 30 falls to the set pressure. The system as so far described will operate normally as long as the pressure of the gas supply at 26 does not fall below the pressure which the regulator is set to maintain at its outlet 27 and at the carburetor gas intake 16. For purposes of illustrative description will be assumed that the regulator is adjusted (e. g. by setting the adjustment 31 of spring 29) to normally maintain at outlet 27 a pressure equal to one-quarter inch of water below atmospheric pressure. The Venturi throat depression, in normal engine operation, is considerably greater than one-quarter inch, and valve 15 is set so that the pressure differential across the set valve opening is sufficient to draw in from 16 the volume of fuel required to properly carburet or make a combustible mixture with the air passing through the venturi. Utilizing gas of such a relatively low heat content, the required full volume is relatively large and valve 15 is set wider open than it would be for such a fuel, say, as butane.

If the gas supply at 26 becomes exhausted to the point that its pressure falls below the set delivery pressure of the regulator, the suction at 16 immediately tends to lower the pressure in 20 and in regulator chamber 30 to a pressure which is increasingly lower than the set pressure. Using an ordinary regulator, in which valve 28 remains open for any pressure below the set pressure, the continued operation will also lower the gas pressure in 21 and 22 (assuming that 21 connects openly with tank 22). However, it is immaterial whether valve 28 remains open or not; in any case the continued draft on the gas at 16 lowers the pressure at that point and in feed pipe 20. It may here be remarked that, pipe 20 being large enough that there is no appreciable pressure drop of gases flowing through it, the pressure in that pipe is always the same as at gas intake 16. For that reason pipe 20 may be regarded as a part or extension of the gas intake 16 which connects with gas draft port 14 via the restriction at 15.

Connecting also with gas intake 16 (here shown as connecting via intake pipe 20) is a second intake or feed pipe 40 which connects, via another

restriction at adjustable valve 42, with the delivery pipe 44 of a second pressure regulator R! which takes its gas supply through inlet pipe 45 at suitably high pressure (say six or eight water-inches) from any suitable source, as tank 48. Regulator R! may also be any suitable ordinary regulator, here shown schematically the same as R (same numerals applied to corresponding parts). Regulator R!, however, is set to deliver its gas at a pressure which is preferably slightly, but definitely, below the delivery pressure of R. In the particular illustration at hand, with R set at one-quarter inch depression, R! is set to deliver at say, one-half inch depression.

I have said that the set delivery pressure of R! is definitely below that of R. I mean by that, that the difference between these set pressures is large enough that with the set delivery pressure of R present in intake 16, 20 and in the delivery pressure chamber 30 of R!—that is, with regulator R operating normally—valve 28 of R! will be positively closed so that R! does not normally feed gas to the intake. A one-quarter inch difference has been found to be practically ample for that purpose. How much larger the difference may be depends in practice on how much drop from normal operating pressure at intake 16 can be tolerated. In feeding an internal combustion engine, any considerable pressure drop at 16 may stop the engine and thus stop the fuel draft at 14. In feeding other devices (see below) where continuance of draft at 14 does not depend, or depend at all critically, on the amount of gas drawn in at 16, the pressure difference may be quite large. But for practical purposes and for uniformity of operation of the device or unit which is drawing the fuel, it is sufficient and preferable that the difference between the set delivery pressures of the two regulators be substantially just sufficient to insure tight closing of the valve of regulator R! when R is operating normally.

The fuel gas supplied to regulator R! has a heat content per cubic foot greater than that of the gas supplied to regulator R. Almost any commonly used fuel gas will satisfy that requirement; natural gas, producer gas, butane, etc. are examples. Butane, which has a heat content of about three thousand B. t. u. per cubic foot, may be taken as illustrative. Because of its higher fuel content it needs to be fed to intake 16 in smaller volume than the gas of low heat content. Consequently the restriction at control valve 42 is adjusted to such size that, acting in series with the restriction at valve 15, the correct amount of the high heat gas is fed. When two gases having a large disparity of heat content are being used, such as those here named, the orifice at 42 is adjusted to a size considerably smaller than that at 15. In the following description of operation, it is assumed that all pipe connections, such as 20, 40, 44, are large enough that pressure drops due to flow through them are negligible.

In considering the operation of the fuel feeding system, it is convenient initially to consider the Venturi suction pressure at 14 to be substantially constant, and to assume that pipe 21 which feeds regulator R connects directly with tank 22. Under normal operation, when the supply pressure at 26 is ample, the pressure in line 20 and intake 16 is substantially the set delivery pressure of regulator R, so that the pressure drop across the orifice at valve 15 is determinate. That definite pressure drop, together with the set orifice of

valve 15, determine the normal rate of primary fuel flow. Regulator R! remains closed, and there is therefore no flow of supplementary fuel and no pressure drop at valve 42.

If now the supply pressure at 26 drops slightly below the set delivery pressure of regulator R, the actual delivery pressure at gas intake 16 is lowered correspondingly. That reduces slightly the pressure drop available across the orifice at 15, and hence reduces the rate of fuel flow from 20 to carburetor 12. That reduction of flow continues with continuing decline of supply pressure 22 until the pressure at 16 and in 20 becomes just equal to the set delivery pressure of supplementary fuel regulator R!. At that pressure, regulator R! opens and maintains the delivery pressure in line 44 at the set lower value. At first, that action results in the delivery of relatively little of the supplementary fuel to 16, since the pressure drop available across the orifice at valve 42 is relatively small. Nevertheless there is some flow of supplementary fuel, which tends immediately to counteract the effect of the decreasing flow of primary fuel. In other words, the transfer of operation from primary to supplementary fuel begins when the primary supply pressure at 26 allows the pressure at 16 to drop to the set delivery pressure of supplementary regulator R!. That pressure will be referred to as the initial transfer pressure, since it is the pressure at which transfer from primary to supplementary fuel is initiated.

In practice the initial transfer pressure is preferably only slightly (say $\frac{1}{4}$ inch of water) less than the normal operating pressure at 20, as already explained. On the other hand, the normal Venturi pressure at 14 is very considerably (say several inches of water) below that pressure at 16. Hence (assuming regulator R to be of sufficient capacity) a reduction in primary fuel pressure can result in only a relatively small reduction in primary fuel flow (say, about 5%) before the initial transfer pressure is reached, with resulting enrichment of the fuel by admixture of the relatively rich supplementary fuel.

If the supply pressure at 26 continues to decline, tending to carry the pressure at 16 down with it, the pressure drop across the orifice at 42 gradually increases. That increase of pressure differential across 42 leads to increased flow of supplementary fuel from 44 to intake 16. Thus the supplementary fuel gradually replaces the primary fuel at the gas intake, and thereby maintains effective fuel supply to the engine or other fuel consumer 10.

As the flow of supplementary fuel increases, it tends more and more to maintain the pressure at 16, and thereby to reduce the flow of primary fuel from tank 22 to 16. That effect becomes more pronounced as supply pressure from 22 continues to decline, until a definite point is reached at which the pressure at 16 has sunk to a value that is fully maintained by the flow of supplementary fuel alone. Primary fuel then ceases to flow through regulator R, even though regulator valve 28 remains open. The system has then been transferred completely to operation by the supplementary fuel. The pressure at 16 at which that takes place is here called, for convenient reference, the final transfer pressure. Any decrease of primary fuel supply pressure at 16 below the final transfer pressure (which might be caused, for instance, by other drafts on the gas in 22, if pipe 21 connects directly with 22) has no effect upon the operation

of the fuel system, since pressure at 16 is maintained by the flow of supplementary fuel. Assuming regulator R₁ and the pipe connections to be of sufficient capacity, the only effect of such a pressure drop in 22 would be a reverse flow of high heat gas from 20 to 22. The same condition might be set up, for instance if the operating level of unit 10 is lowered while regulator R₁ is feeding the system. But any such back flow may be prevented by the simple expedient of installing a check valve any place in the primary feed line between tank 22 and the point where 5 40 joins 20.

Any increase in primary fuel supply pressure at 16 tends to carry the system back over the course that has just been described. In practice the system rapidly stabilizes in response to the existing primary supply pressure, the ratio of primary to supplementary fuel fed to Venturi inlet 14 automatically accommodating itself to varying supply conditions.

The description so far, for purposes of simplicity, has assumed that feed pipe 21 for regulator R connects directly to supply 22. Under those conditions the pressure in the supply 22 may at 10 times fall below atmospheric; and that is to be prevented in order to avoid the hazard of air leaking into the tank. For that purpose a valve such as that shown at V is installed in pipe 21. As shown the valve has a diaphragm chamber 50 with a diaphragm 51 exposed to atmosphere and also preferably loaded, as with a spring 52 so that valve 53 will close on pipe 21 at a pressure somewhat above atmosphere. Pipe 21a leads from tank 22 to chamber 50; so that valve 53 will be open as long as pressure in 22 is somewhat above atmospheric and close whenever the tank pressure drops below that. The action of the system with this valve included in it is the same as before described, except that the complete change-over from primary to secondary supply may be more abrupt, depending on the capacity of the piping system including that of pipe 21 between regulator R and valve V. Under no 15 conditions, however, can the tank pressure at 22 be reduced below that for which valve V is set. And, that valve V being set to close at a pressure higher than that which either regulator maintains (or which regulator R₁ particularly maintains) at intake 16, there cannot be at any time 20 any back flow of gas from supply 48 into supply 22.

The final transfer pressure (under given conditions of engine operation) is definitely determined by the various parameters of the system. It lies between the Venturi pressure at 14 (considered constant) and the set delivery pressure of regulator R₁; and its value is determined by the orifices at valves 42 and 15 acting as a pressure dividing network. The rate of flow of supplementary gas under that condition is such that the sum of the two resulting pressure drops at the two valves 42 and 15 equals the total pressure differential from 44 to 14. The ratio of the pressure drops at the two valves equals the inverse ratio of their effective cross-sectional orifice areas. As already stated, the orifice of valve 42 is ordinarily considerably smaller than that of 15, so that the pressure drop at 15 is much smaller than that at 42. The final transfer pressure may then be only slightly higher than the Venturi pressure at 14.

However, if the two gases are more nearly equal in their heat content the orifices at 42 will be more nearly equal to that at 15. If the ratio of

the heat contents were two to one, orifice 42 would be equal to orifice 15; and for a lower ratio, the orifice at 42 would be the larger. With orifice 42 relatively larger, the pressure drop across it is relatively smaller and the final transfer pressure at which regulator R solely feeds the gas intake 16 will be relatively higher.

The process of transferring operation from primary to supplementary fuel takes place very gradually as the primary supply pressure falls below normal, that is, below the set delivery pressure of regulator R₁. Only a relatively slight reduction (typically about $\frac{1}{4}$ inch of water) takes place before the initial transfer pressure is reached, and feeding of supplementary fuel begins. But a relatively large further reduction in primary supply pressure (typically 4 or 5 inches of water with valves 15 and 42 set for gases having the ratio of heat content here being illustratively considered) may be required before the final transfer pressure is reached. Throughout that latter reduction, the supplementary fuel progressively provides a larger and larger proportion of the fuel fed to Venturi inlet 14. Because of the gradualness of that transfer, the system tends to stabilize itself effectively at virtually any existing rate of supply of primary fuel to container 22. If that rate of supply changes in either direction, the ratio of primary to secondary fuel fed by the system changes accordingly in such a way as to use all, or as much as possible, of the available primary fuel.

Although the above description of typical operation of my system has been based for clarity upon the supposition of a constant Venturi pressure at 14, it will be understood that variations in that pressure within the operating range of the feed system do not affect the principles of the operation.

As has been implied, the restriction at valve 15 may be physically a part of the engine or other gas consuming unit, or physically a part of the feed system which is applied to the unit. In any case, the feed system functionally includes the restriction at 15, restricting the gas intake 16; but from a practical or commercial standpoint the system may be regarded as one which is adapted to feed gases to such a restricted intake 16.

Both the restrictions at 15 and 42 are conveniently in the form of adjustable valves, but can be orifices or passages of chosen sizes.

I have spoken of the regulators being set to deliver at defined pressure. Although that setting may conveniently be done by adjustments such as described, it may also be and commonly is done by proper selection of the appropriate design factors of the regulators and/or by selection of springs of proper strengths.

I have mentioned other gas-drawing units which may be fed by my system. A gas and air mixer for any purpose, say for a burner, may be taken as typical. It may be assumed for instance that element 10 of the drawing represents a gas burner, and that air under pressure is supplied to the air intake 9 of carburetor (mixer) 12. Depending on air velocities through the venturi 13, the relative depression (the negative velocity head) at 14 may be such that the pressure at 14 is above atmospheric. (The same of course may be the case when an engine is being fed with air under pressure.) In any such case the set delivery pressure of both R and R₁ may be above atmospheric, but the system, with the same relative settings as before described, will

operate in the same manner. And the burner unit is illustrative of any gas drawing unit which does not depend for its gas drawing operation on continued uniform gas feed. In any such case the pressure difference between the two regulators may be relatively large.

The system as described may be modified for the successive supplies of two or more supplemental gases simply by duplicating the described supplemental system, 40-48, connecting 40 of the duplicate supplemental system or systems to intake 16, 20, and setting the several regulators of the several supplemental systems to deliver at successively lower pressures.

I claim:

1. In a multiple gas feed system for feeding combustible gases of different heat contents to a gas using unit, the combination comprising: a first pressure regulator adapted to be set to insure a predetermined delivery pressure and to have the inlet thereof connected to a pressurized source of gas of relatively low heat content; a first conduit connected to the outlet of said first regulator for delivering gas to the gas using unit; a flow restriction in said first conduit for throttling the flow of low heat content gas to rates required by the using unit; a second pressure regulator adapted to be set to insure a delivery pressure less than that of said first regulator and to have the inlet thereof connected to a second pressurized source of gas of relatively high heat content; a second conduit having one end thereof connected to the outlet of said second regulator and the other end thereof to said first conduit upstream of said flow restriction therein; and a flow restriction in said second conduit which acts in series with said first conduit flow restriction for throttling the flow of high heat content gas to rates required by the using unit.

2. The structure defined in claim 1 in which the using unit draws gas at sub-atmospheric pressure and including a gas inlet conduit connected to the inlet of the first regulator, and pressure-responsive valve means controlling said inlet conduit, said valve means being closed at conduit pressures below substantially atmospheric pressure and open at pressures thereabove.

3. In a multiple gas feed system for feeding combustible gases of different heat contents to a carburetor suction port of an internal combustion engine, the combination comprising: two pressure regulators one adapted to be set to insure a higher delivery pressure than the other and to have its inlet connected to a pressurized source of low heat content gas, and the other lower delivery pressure regulator adapted to have its inlet connected to a pressurized source of high heat content gas; feed conduits connecting the outlets of said regulators to the suction port; means restricting the suction port for throttling the flow of low heat content gas therethrough to rates required by the engine; and a restriction in the feed conduit from said other lower pressure regulator which acts in series with said suction port restriction to throttle the flow of the high heat content gas to rates required by the engine.
